Primary Examiner — Shannon W Morgan*Assistant Examiner* — Kellianne M Shaver(74) *Attorney, Agent, or Firm* — Dunlap Bennett & Ludwig, PLLC; Anna L. Kinney(57) **CLAIM**

The ornamental design for a stove fuel adapter, as shown and described.

DESCRIPTION

FIG. 1 is a top perspective view of a stove fuel adapter showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The evenly spaced broken lines shown in the drawings depict portions of the article that form no part of the claimed design. The long-short-long broken lines shown in the drawings depict a boundary that forms no part of the claimed design.

1 Claim, 4 Drawing Sheets(56)
